CLAIM

The ornamental design for a dish rack, as shown and described.

DESCRIPTION

FIG. 1 is a front perspective view of a dish rack showing our new design;

FIG. 2 is a front elevation view thereof;

FIG. 3 is a rear elevation view thereof;

FIG. 4 is a right side elevation view thereof;

FIG. 5 is a left side elevation view thereof; and,

FIG. 6 is a top plan view thereof.

A bottom view is not provided as no part of the bottom view is claimed.

The broken lines depict portions of the dish rack that form no part of the claimed design.
